JOSEPH KAKALEY, OF HAZLETON, PENNSYLVANIA.

LETTER SHEET AND ENVELOPE.

Application filed April 26, 1924. Serial No. 709,238.

The object of the invention is the construction of an envelope from a single blank of paper which may be used as a letter sheet and which, when folded, will constitute two separate compartments, one for first class mail and the second for second class mail or the compartments may be employed for contributions in churches or the like.

To the attainment of the foregoing, the invention consists in the improvement as hereinafter described and definitely claimed.

In the drawing:—

Figure 1 is a view of the blank from which the envelope is formed.

Figure 2 is a plan view showing the first step in the folding of the envelope.

Figure 3 is a similar view showing the next step.

Figure 4 is a plan view showing the envelope folded but the sealing flap extended.

Figure 5 is a plan view of the envelope completely folded, looking to the rear of the structure disclosed in Figure 4.

Figure 6 is a sectional view on an enlarged scale, and approximately on the line 6—6 of Figure 5.

As disclosed by Figure 1 of the drawing, my improved envelope is formed from a single sheet of material, the body of which being provided with transverse score lines to divide the same into a face portion 1, a sealing flap 2, a sheet 3 and an end flap 4. The sealing flap 2 has its edges coated with an adhesive substance. The flap 4 has an extension 5, divided therefrom by a score line 6. On the face 1, the body is provided with lateral extensions divided from the face by score lines and providing flaps 7 and 8 respectively, each of which having its face adhesively coated.

In forming the blank into an envelope the

flap 5 is folded over the rear face of the end 4, and the end 4 is then folded on the score line that divides the same from the sheet 3. The sheet 3 is then folded on its score line which divides the same from the face 1 and the flap 5 is adhesively secured on said face. The flap 7 is next adhesively secured to the sheet 3. This provides the compartment 9 of the envelope. The flap 2 is adhesively connected to the flap 7 and the sheet 3 to produce the second compartment 10. When the device is employed for contributions or for second class mail, the flap 8 is extended or folded under the flap 2. When the device is to be employed for first class mail or to provide two sealed compartments the flap 8 is adhesively connected to the sheet 3 before the flap 2 is folded thereover and adhesively secured thereto.

Before being folded into envelope form, the inner face of the body may be employed for writing purposes.

Having described the invention, I claim:—

An envelope comprising a blank having a body portion, said body portion being divided by transverse scores into four sections, each of the end sections being provided with gummed tabs on their extremities, one of the center sections having two side tabs, the said blank being adapted to be folded on the transverse lines of score, the gummed tab of one end being secured to the face of the center section having the side tabs, the said tabs then being folded over and secured to the back of the other center section, the remaining end being secured to the same said center section thereby forming a duplex envelope.

In testimony whereof I affix my signature.

JOSEPH KAKALEY.
